(57) **CLAIM**

The ornamental design for a display screen with graphical user interface, as shown and described.

DESCRIPTION

This application is related to U.S. Utility patent application Ser. No. 18/097,022, filed Jan. 13, 2023 and entitled “Order Assembly for Multiple Points of Sale,” which is incorporated by reference herein for all purposes.

FIG. 1 is a first image of a display screen with graphical user interface showing the new design;

FIG. 2 is a second image of the display screen with graphical user interface showing the new design;

FIG. 3 is a third image of the display screen with graphical user interface showing the new design; and,

FIG. 4 is a fourth image of the display screen with graphical user interface showing the new design.

The evenly spaced broken lines illustrate portions of the graphical user interface and environment that form no part of the claimed design. The dash-dot lines illustrate the boundary of the display screen and form no part of the claimed design.

The graphical user interface includes a sequence of the images in FIGS. 1-4, with the user interface transitioning between the images shown in FIGS. 1-4. The process or period in which one image transitions to another image forms no part of the claimed design.
